UNITED STATES PATENT OFFICE.

WILLIAM SPARKS, OF JACKSON, MICHIGAN, ASSIGNOR, BY MESNE ASSIGNMENTS, TO STEWART-WARNER SPEEDOMETER CORPORATION, OF RICHMOND, VIRGINIA, A CORPORATION OF VIRGINIA.

LIQUID-FEEDING DEVICE.

Application filed June 20, 1921. Serial No. 479,082.

To all whom it may concern:

Be it known that I, WILLIAM SPARKS, a citizen of the United States, and resident of Jackson, in the county of Jackson, in the State of Michigan, have invented new and useful Improvements in Liquid-Feeding Devices, of which the following, taken in connection with the accompanying drawings, is a full, clear, and exact description.

10 This invention relates to certain improvements in liquid feeding devices for use particularly in supplying liquid fuel to internal combustion engines of automobiles and the like, in connection with which it is very often desirable to have the primary fuel tank carried on the vehicle at a level below the carburetor.

15 The main object of the invention is to provide a device of relatively simple construction and high efficiency in automatic operation, with particular relation to the construction of the vacuum tank portions thereof, to which the liquid fuel is elevated, as by suction produced by the engine and intermittently discharged therefrom, to be sent by gravity to a vaporizing device, for instance, to the float chamber of a commercial carburetor.

20 A further object relates to the particular form, arrangement and method of operation, of the valve devices of the structure, whereby positive automatic operation is attained.

25 A further object relates to the positive actuation of the air inlet valve, the air exhaust valve, and the valve controlling communication between the upper and lower chambers of the tank structure, by a single lever mechanism whereby a particular timing operation is secured.

30 Other objects and advantages relate to the details of construction and operation of the device, as will more fully appear from the following description taken in connection with the accompanying drawings, in which:

35 Figure 1 is a vertical sectional view through the vacuum tank structure illustrating the valve devices in one position of operation taken on line 1—1 of Figure 3.

40 Figure 2 is a similar sectional view of the same structure illustrating the valve devices in their other operative position taken on line 2—2 of Figure 3.

Figure 3 is a sectional view on line 3—3, 55 Figure 1.

The vacuum tank, as shown comprises a substantially cylindrical casing —1— having its lower end closed by an end wall —2— and its upper end closed by cover —3—, the lower end —2— and the cover —3— being secured to the cylindrical casing —1— in any suitable manner, as that illustrated. The chamber so formed is divided into an upper and a lower chamber —4— and —5— respectively, the upper chamber adapted to be directly connected to a source of liquid fuel not shown, and to feed liquid fuel intermittently to the lower chamber in accordance with the capacity of the apparatus and the needs of the motor to be supplied with fuel.

55 For this purpose the cover —3— is penetrated by a fuel inlet pipe —6—, a suction or exhaust connection —7—, and a somewhat elongated tubular nipple —8— provided with a laterally extending air-inlet port —9—, such air inlet port being controlled by a piston valve —10— actuated in a manner to be hereinafter described.

60 The cross wall —11— which forms the bottom of the chamber —4— and the top of chamber —5— is provided with an opening or passageway which permits communication between said chambers and this passageway may be formed in a nipple —12— which has a guideway —13— for the lower end of a valve stem —14— which carries the valve —15— controlling such passageway through the nipple —12— and at its upper end is loosely connected to the piston —10— to permit a certain limited relative movement.

65 The valve stem —14— at an intermediate point thereon is formed preferably with a pair of spaced flanges or projections —16— forming between them a groove or a space for the reception of the slotted end of a lever —17—, the opposite end of which lever is pivoted upon a pair of depending lugs —18— formed in connection with a plate-like member —19— which may be secured to the cover —3— of the tank structure. The lever —17— at an intermediate point has an opening through which the stem of the valve —20— passes. This valve controls the communication between the upper chamber —3— and the suction pipe

or line —7—. This valve, as shown, has a loose sliding connection with the lever —17— and may, as stated, have its stem extend through said lever so that the valve 5 is supported by the lever when in open position.

It will be understood from the description so far given that the valve stem —14— is in effect carried by and adapted to be 10 actuated by the lever —17—, and this actuation or movement by means of lever —17— is effected automatically through the rise and fall of a float —21— which may have a stem —22— mounted at its 15 lower end in a guideway formed in connection with cross-plate —11— and its upper end pivotally connected to a lever —23— which lever has its opposite end pivoted upon the downwardly projecting lugs —24— 20 formed in connection with the plate —19— in substantially the same manner as lugs —18—, the lugs —24— being spaced apart a distance somewhat greater than the distance between the lugs —18—, so that the 25 arms —25— and —26— and the lever —23— can move outside the lugs —18— and each of the arms —25— and —26— is provided with an enlarged part —27— and —28— respectively, which may, as shown, be of 30 cylindrical form and project inwardly from the respective arms so as to lie beneath the enlarged flange part —29— on the stem of valve —20— and engage said enlarged part to elevate said valve to closed position when 35 the lever is moved upwardly by rise of float —21—.

It will be seen that the suction valve —20— opens by gravity when the lever —17— has moved downwardly to permit 40 such movement, or if the suction should be sufficient to hold it closed against gravity, the final downward movement of lever —23— as actuated by the float, will move the valve from its seat. When open, the 45 suction valve remains in that position until as the float —21— gradually rises, the projecting parts —27— and —28— come into contact with the flange part —29— and gradually raise the said suction valve —20— 50 from its position of rest upon the lever —17— and at a pre-determined position of the float —21—, said suction valve is moved to closed position.

The valve —15— and the valve —10— are 55 always either in substantially completely open or in substantially completely closed position and are moved to and held in one or the other of those particular positions by means of a snap-over spring action, embodying springs —30—, as best shown in Figure 60 3, connecting the opposite ends of the levers —17— and —23— respectively.

It will be seen that as the float —21— moves upwardly carrying with it the lever 65 —23—, as soon as the line of spring con-

nexion between the end bars —31— and —32— of the respective levers is above the pivot of the lever —17— upon the lugs —18—, then the springs will cause an upward movement of the slotted end of lever —17— carrying with it the valve stem —14— and valves —15— and —10— to open the air inlet —9— and the communication between the chambers —3— and —4— through nipple —12—, the nipple being 70 provided with any suitable discharge opening, as the lateral discharge opening —33—. When the operation is reversed and the float —21— moves downwardly, the valve —20— is held in closed position by the 75 suction, and does not start opening until forced open by arm —17—, and the valves —10— and —15— remain in open position until the springs —30— are moved past the pivot of the lever —17— upon the lugs —18—, at which time the springs —30— will snap the slotted end of lever —17— downwardly carrying the valve stem —14— with it, positively moving the valve —15— and valve —10— to closed position, and the valve —20— to open position. Immediately suction is applied to the chamber, the application of that suction to the valve —10— will substantially neutralize any 80 tendency to move the valve —15— from its 85 closed to open position, and for this purpose it is desirable that the exposed surface area of the valve —10— should have a relation with respect to the surface area of valve —15— so that combined with the 90 tensile power of springs —30— the suction applied to valve —10— will neutralize the tendency of the suction to move valve —15— from closed to open position, during 95 filling of the chamber —4—.

As shown, the lower chamber —5— is connected to the atmosphere by a vent pipe —34— which penetrates the cap —3— of the tank structure to maintain at all times atmospheric pressure in the lower chamber —4—. The fuel discharges from the opening —35— by gravity to the carburetor, and a second opening —36— is provided which may be used as a drain and should be provided with any suitable controlling device as a valve, or other connection, in a manner well known. The operation of this structure is positive, automatic and reliable in its elevation of and supply of liquid to the chamber —5— and 100 the consuming means as a carburetor.

Although I have shown and described a specific construction as illustrative of a perhaps preferred embodiment of my invention, I do not desire to limit myself to the 105 details of construction, form or operation of the device, as various changes and modifications may be made in the same without departing from the invention as set forth 110 in the appended claims.

What I claim is:

1. In a fuel feeding device in combination with a vacuum chamber and a second chamber into which the vacuum chamber discharges liquid, a suction connection, a fuel supply connection, and an atmosphere inlet connection to the vacuum chamber; a valve controlling liquid outlet from the vacuum chamber to the second chamber opening inwardly with respect to the vacuum chamber; a valve which controls the atmosphere inlet to the vacuum chamber opening outwardly with respect to said chamber; operating connections between said liquid outlet valve and the atmosphere inlet valve for causing them to move simultaneously in opening; whereby the pressure resulting from the suction tending to hold the atmosphere inlet valve closed opposes the pressure resulting from the same suction tending to open the outlet valve; the areas of said valves exposed to said pressure being approximately equal, and that of the atmosphere inlet valve being at least as great as that of the liquid outlet valve; a selected one of said two last mentioned valves being constructed for sliding movement along its seat at closed position; whereby in the closing movement said selected valve may reach closed position before the other, without preventing the other from reaching closed position in the same movement; and a float in the vacuum chamber operatively connected for opening said inlet and outlet valves by the rise of the float.

2. A fuel feeding device comprising an upper chamber and a lower chamber, means of communication between said chambers, a valve controlling such means of communication, an air inlet to the upper chamber, a valve controlling said air inlet, a valve stem common to both of said valves, a pivoted lever for moving the valve stem to actuate said valves, a second pivoted lever, spring connections between said levers, float controlled means for moving said second lever, a suction line communicating with the upper chamber, a valve controlling said suction line, said valve having a slidable relation with the said first named lever, and means in connection with the second named lever for sliding said valve with respect to the first lever.

3. A fuel feeding device comprising a chamber having an outlet therefrom, a valve controlling said outlet, a suction connection with said chamber, a valve controlling said

connection, an air inlet to said chamber, a piston valve controlling said air inlet, and means for moving the suction valve to substantially closed position before any opening movement of said other valves is effected.

4. A fuel feeding device comprising a chamber having an outlet leading therefrom, a valve controlling said outlet, an air inlet to said chamber, a valve controlling said air inlet, a lever for actuating said last mentioned valve, a second lever, a float connected to the second lever, and a spring connection between said levers whereby the first named lever is actuated to move said valve to either closed or open position at predetermined positions of the first named levers actuated by said float.

5. A fuel feeding device comprising a chamber having an outlet leading therefrom, a valve controlling said outlet, an air inlet to said chamber, a valve controlling said air inlet, a lever for actuating said second mentioned valve, a second lever, a float connected to the second lever, and a spring connection between said levers whereby the first named lever is actuated to move said valve to either closed or open position at predetermined positions of the first named levers actuated by said float, a suction connection with said chamber, and a valve supported by said first named lever and controlling the suction connection.

6. A fuel feeding device comprising a chamber having an outlet leading therefrom, a valve controlling said outlet, an air inlet to said chamber, a valve controlling said air inlet, a lever for actuating said valve, a second lever, a float connected to the second lever, a spring connection between said levers whereby the first named lever is actuated to move said valve to either closed or open position at predetermined positions of the first named lever actuated by said float, a suction connection with said chamber, a valve supported by said first named lever and controlling the suction connection, and means in connection with the second named lever for moving said suction valve to substantially closed position independently of the movement of the first named lever.

In witness whereof I have hereunto set my hand this 31st day of May, 1921.

WILLIAM SPARKS.

Witness:

LILLIAN E. WUNDERLICH.
